UNITED STATES PATENT OFFICE.

JOSEPH STURIALE, OF NEW YORK, N. Y.

NON-REFILLABLE BOTTLE.

1,256,948.

Specification of Letters Patent. Patented Feb. 19, 1918.

Application filed April 1, 1915. Serial No. 18,429.

To all whom it may concern:

Be it known that I, JOSEPH STURIALE, a subject of the King of Italy, and a resident of the city, county, and State of New York, have invented a new and useful Non-Refillable Bottle, of which the following is a specification.

My invention relates to improvements in non-refillable bottles, and has for its object 10 to provide a container for liquids, of simple construction, with no complicated or expensive parts, which can be made at small cost and which cannot be refilled after the contents have been taken therefrom.

15 Many of the so-called non-refillable bottles can be refilled if they be submerged in a liquid and manipulated so that the various parts are moved with relation to their normal positions, but in my device the entrance 20 to the container is always sealed whenever it is in a position whereby a liquid would flow inwardly by gravitation.

My invention is further described in the following specification and illustrated in the 25 drawings annexed hereto.

Figure 1 is a vertical sectional view through the neck of a bottle containing my device, the body of the bottle being broken away.

30 Fig. 2 is a vertical sectional view through the neck of a bottle showing my device in elevation.

Fig. 3 is a view similar to Fig. 1 showing the bottle in a tilted position and with the 35 various parts in the positions they assume when liquid is being poured from the bottle.

Figs. 4, 5 and 6 are respectively, transverse sectional views taken on the line 4—4, 5—5 and 6—6 in Fig. 1.

40 As shown in the drawings, the bottle neck 10, is provided with an annular shoulder 11 which forms a stop to receive the lower edge of the cylindrical member 12. This latter member 12 has a plurality of ribs 13 45 which form a guide for the cone shaped member 14 adapted to fit snugly in the opening 16 of the lower portion 17 of the member 12, thus forming a water tight connection when the bottle is in an upright position.

50 The member 12 is also provided with a head 18 which may be secured thereto by threading or other similar means. This head 18 has a neck portion 19 provided with an opening 20 and a plurality of slots 21, 55 the object of these slots being to make it impossible for the flat end of the cone

shaped plug 14 to entirely prevent the egress of liquid from the bottle when the latter is tilted.

The valve member 22 consists of a disk 60 like object adapted to fit over the opening 20 and held in place when the bottle is not being poured from by the ball 23 which is guided into position by the ribs 24 on the cylindrical casing 25 which is secured at its 65 lower end to the member 12.

The upper part of my device consists of a plate 26, having a neck portion 27 with notches 28 at intervals to receive the ribs 24 on the casing 25. The said plate 26 also has 70 an opening 29 to permit the egress of the liquid. In the upper part of the neck of the bottle is an offset portion 30 provided with a plurality of slots 31 in which the extensions 32 of the plate 26 are adapted to 75 fit. I also show the usual form of cork 33 in the neck of the bottle.

As shown in Fig. 3, the bottle is in a tilted position and as may be seen therein, the parts inside the neck of the bottle assume 80 positions which will permit the liquid contents of the bottle to emerge freely along the course and in the direction indicated by the arrows.

In constructing my invention it is preferable to assemble all the parts outside of the bottle, with the exception of the upper plate 26. When thus assembled it may be inserted in the neck of the bottle so that the lower part 17 of the member 12 rests on the 90 shoulder 11. The upper plate 26 may then be positioned, and as the slots 31 converge inwardly the plate 26 can be jammed into position, thereby locking all the other parts in their proper relative positions. 95

I also show in Fig. 4 another method of holding my device in the neck of the bottle, consisting of an annular groove 33 in the said neck into which the projections 32 of the plate 26 may be inserted through the 100 slots 31. Then by giving the plate 26 a quarter turn the projections 32 will rest in the said groove 33 so that it is locked against inward or outward movement.

My device can be made of any suitable 105 material such as porcelain or glass thereby avoiding the use of metal and keeping down the expense of manufacture, and the bottle or other container cannot be filled by emersion or by pressure, when equipped 110 with my device, as set forth in the appended claim.

I have also found it practical if desired to inclose my device as shown in a casing which could then be inserted and secured within the neck of the bottle by cementing 5 or similar means.

I claim:

In a non-refillable bottle, the combination of a bottle neck having an off-set portion provided with a plurality of vertical slots, 10 a sectional valve casing positioned within said neck, valve means carried within said casing, one section of said casing having ribs, a plate positioned within said neck, said plate having extensions upon its periphery,

said extensions wedging within said grooves, 15 whereby said plate will be held against accidental movement, a hollow neck formed on said plate and projecting inwardly therefrom, said neck having notches in its inner end, said ribs projecting into said notches, 20 whereby said casing will be positively held against accidental movement.

In testimony whereof I have hereunto set my hand this 8th day of October, 1914.

JOSEPH STURIALE.
